UNITED STATES PATENT OFFICE.

CLARENCE C. KEFFER, OF UNION CITY, INDIANA.

HOLDER FOR MEDICINE-BOTTLES AND ABSORBENT ROLLS.

1,171,210.

Specification of Letters Patent.

Patented Feb. 8, 1916.

Application filed April 1, 1915. Serial No. 18,591.

To all whom it may concern:

Be it known that I, CLARENCE C. KEFFER, a citizen of the United States, resident of Union City, in the county of Randolph and 5 State of Indiana, have made a certain new and useful Invention in Holders for Medicine-Bottles and Absorbent Rolls; and I declare the following to be a full, clear, and exact description of the same, such as will 10 enable others skilled in the art to which it appertains to make and use the invention, reference being had to the accompanying drawings, and to letters or figures of reference marked thereon, which form a part of 15 this specification.

Figure 1 is a perspective view of the invention. Fig. 2 is a detail perspective view of the bottle holder. Fig. 3 is a detail plan view of the blank for the bottle holder. Fig. 4 20 is a detail cross section partly broken away and taken through one of the upright clasping arms. Fig. 5 is a similar view taken through one of the horizontal bracing arms. Fig. 6 is a detail perspective view of the 25 bevel ended absorbent roll.

The object of the invention is to provide an improvement in devices for preventing acid or other strong or discoloring liquid 30 from dropping upon the patient's clothes, such improvement being designed particularly for the use of dentists.

The invention consists in the novel construction and combinations of parts, as hereinafter set forth.

In the accompanying drawings the numeral 2 indicates the four-sided prismatic bottle usually employed by dentists for holding acids or other strong liquids, and 3 designates a cross-form holding base for such 35 bottle, this holder being made of thin or sheet metal. In making this holder a blank is provided such as is illustrated at 4, said blank having four broad and short portions

5 projecting from its central rectangular portion 6, and four longer portions 7 projecting from the central portion, between the portions 5. In the finished holder, the longer portions or arms 7 remain in the plane of the flat central portion, and the short and broad portions 5 are bent upward, 45 between the arms 7, substantially at right-angles to the central portion, sufficiently toward each other on opposite sides to provide clasping members or arms to engage the sides of the bottle and hold it in 50 position against the central base portion 6, said clasping members being spaced apart 55 from each other, as shown at 6'. The holding base, therefore, has four horizontal 60 bracing arms 7 projecting from its central portion at right-angles to each other, and serving to extend the base materially, to prevent the bottle held thereby from being upset, and four clasping arms projecting upward. This bottle holder is designed also to 65 hold in inclined position a small roll of absorbent cotton 9, having a beveled end located between the bottom of the bottle and the holder base.

I claim:

A cross-form sheet metal bottle holder, comprising a central horizontal base having four long broad horizontal bracing arms extending from its sides in the plane of said base and at right angles to each other, and four clasping arms projecting upward from said base, each clasping arm being located between two bracing arms and the clasping arms being spaced apart from each other.

In testimony whereof I affix my signature, in presence of two witnesses.

DR. C. C. KEFFER.
